FIG. 1

The dominant features of my design for a portable mixer or the like reside in the portions shown in full lines.

I claim:

The ornamental design for a portable mixer or the like, substantially as shown and described.
